UNITED STATES PATENT OFFICE.

GEORGE L. RICE AND LOUIE E. WHITCOMB, OF CHICAGO, ILLINOIS, ASSIGNEES TO
INTERNATIONAL HARVESTER COMPANY, A CORPORATION OF NEW JERSEY.

FEEDER FOR FIBER BREAKERS.

Application filed February 23, 1927. Serial No. 170 100.

This invention relates to a sliver handling machine and more particularly to a sliver feeder for fiber breaking machine.

In cordage and twine mills, the raw fiber or fibrous plants, such as sisal and the like, are received in bales. These bales are separated or torn apart by hand and the fibrous material is thrown manually onto a conveyer mechanism which leads to a "first breaker", said machine tearing apart and decorticating the fibrous plants and combing them out into a relatively thick, loose sliver, which emerges from the discharge end of the machine, there to be formed into a pile. These piles are usually cylindrical in form with the sliver coiled in spirals, so that the pile can easily be unwound without resulting in a tangle.

These piles from the first breaker are thence moved to a "second breaker" which duplicates the combing and drawing action of the first breaker, but makes a more thorough job of it, the sliver resulting from this second breaker being relatively smaller, and more finely combed. A conveyer mechanism is usually employed to feed the piles from the first breaker into the second breaker. Difficulty has been encountered in lifting the slivers from their piles onto the feeder for the second breaker because this first sliver is very loose and as a result the same easily breaks when being elevated from the floor onto the breaker. These breaks may result from the pulling action of the feeder, or because of the weight of the sliver alone, the sliver, because of its looseness, being unable to stand the strain of these forces. It is, therefore, desirable that a feeder be provided which will efficiently handle these loose slivers and feed them to the second breaker without disjointing or breaking these slivers in the handling process.

Accordingly, the objects of this invention are to provide an improved apparatus, as well as a new method, for handling and feeding slivers to a breaker; to provide a feeder which will have a maximum capacity and will feed from a plurality of piles simultaneously; to provide such an apparatus embodying an improved guiding means for accurately directing the plurality of slivers into the breaker; to provide an improved shield structure for all of the operative parts to prevent injury to attendants, and to keep the fibers out of the driving parts;

and, lastly, generally to improve feeders and methods of feeding in this connection, to the end that slivers may be efficiently and expeditiously handled without disjointing or breaking them. 60

Briefly, these desirable objects are achieved in the feeder of this invention, embodying a main longitudinally arranged feeder conveyer which discharges at one end into a spout for directing the slivers onto 65 the second breaker. The other end of this conveyer is formed into a "camel back" and functions as a means for lifting slivers from a pile adjacent said end of the conveyer. On opposite sides of the main conveyer are 70 arranged a plurality of laterally disposed elevators or conveyers, also with "camel backs", each lateral conveyer serving to lift and feed a sliver from a pile on the floor adjacent each lateral conveyer. Guiding 75 members are arranged at the confluence of each lateral conveyer with the main conveyer in a manner properly to direct the slivers onto the main conveyer. Suitable shields are provided to enclose the driving 80 connections for the conveyers to prevent injury to attendants, as well as to exclude the fibers from these parts. The "camel back" formation of each conveyer functions to support the slivers while they are being 85 lifted from the piles onto the main conveyer, and as a result the slivers, even though loose, cannot become broken or disjointed.

Referring to the accompanying sheets of drawings wherein an illustrative embodiment of the invention has been shown, 90

Figure 1 is a general plan view of the improved feeder, a portion of the second breaker being shown in association therewith; 95

Figure 2 is a side elevational view of the feeder;

Figure 3 is an elevational view of that end of the feeder remote from the breaker;

Figure 4 is an end sectional view taken 100 along the line 4-4 of Figure 1 when looking in the direction of the arrows; and

Figure 5 is a side elevational, skeletonized view, with the conveyers removed, to illustrate the driving parts. 105

The frame of the improved feeder comprises spaced end members 10, tied together by transversely disposed rods 11 and longitudinally disposed rods 12. The frame is generally rectangular in shape, with each 110

member 10 being transversely arranged outwardly from each corner of the rectangle. Each member 10 is formed as an integral casting and embodies an outwardly and upwardly inclined portion 13, these portions reaching to a point a little below the middle of these members. (See Figure 4). These portions 10 merge with upwardly and inwardly inclined portions 14, the portions 14 then merging with laterally inclined portions 15 extending towards a central horizontal table, later to be described, and longitudinally arranged between the members 10. The members 10 are suitably cross braced by integrally cast portions 16. There is thus provided a low point at the mergence of the portions 13 and 14; an intermediate point or hump at the mergence between the portions 14 and 15; and a high point at the end of the portion 15 adjacent to and substantially in line with the table to be described.

The table mentioned is provided by arranging angle iron bars 16' longitudinally along the inner upper ends of the members 10. These bars carry wooden sill pieces 17. Another angle bar 18, reversely disposed however, is backed against the sill pieces, and all of the members 16', 17 and 18 are made fast to the members 10 by bolts 19, as shown in Figure 4. Arranged at spaced intervals along each side of the machine between the end pieces 10 are frame members 10' substantially identical in all respects with the end members 10, except that instead of resting on the floor, they are supported by and connected to the longitudinal tie-rods 12. (See Figures 2 and 5.) Of course, it is to be understood that the angle bars 16, 18, and sills 17 are connected to the upper, inner ends of these intermediate frame members 10' in the same manner as has been described in connection with the mounting thereof on the end members 10. Downwardly bowed, cross pieces 20 extend transversely between each opposed pair of the frame members 10 and 10', said pieces 20 being connected by counter-sunk rivets 21 to the angle bars 18, as shown in Figure 4. Thus is completed what may be called the longitudinal, central table structure.

The frame members 10, remote from the discharge or breaker end of the machine, carry longitudinally disposed castings 22. An opposed pair of these castings is provided, as shown in Figure 5, these castings being identical in all respects and embodying upwardly inclined sides, as shown.

At each side of the machine tie-rods 23 are longitudinally arranged between the members 10, 10' adjacent the upper ends thereof. Similarly, are provided tie-rods 24 and 25 to connect and strengthen the intermediate points of the castings 10 and 10'.

Arranged on the tie-rods 23, 24, midway

between the members 10 and 10' on each side of the machine, are brackets 26 having the same general outline or contour as the members 10 and 10'. The purpose of these brackets will later appear. (See Figure 5).

Suitably journaled in the frame of the machine, adjacent its discharge end, is a transverse shaft 27, carrying a sprocket wheel 28, around which is a chain 29, said chain also being trained around another sprocket wheel 30 on a shaft 31 of the breaker, generally indicated by the opposed rollers 32. This shaft 27 carries a pair of spaced sprocket wheels 33, as best shown in Figure 4, each of said wheels operating an endless sprocket chain 34. These chains extend longitudinally along the central table part of the machine and are additionally trained around sprocket wheels 35 (see Figure 5) on a shaft 36 journaled at the upper end of the machine remote from the breaker. This same end of the machine also carries another but lower shaft 37 and sprocket wheels 38, around which the chains 34 also run. These last-mentioned shafts 36 and 37 are idlers. The chains 34 are generally indicated in Figure 5 by the dash lines, and from this showing, it will be clear that they are endless. These chains have attached to their links, closely arranged, cross slats forming a main longitudinally running conveyor 39, the ends of the slats, as seen in Figure 4, slidably resting on the angle iron bars 18.

The shaft 27, it is to be noted, additionally carries fast thereon adjacent each end, a bevel gear 40, each meshing with a bevel pinion 41 fast on a shaft 42, there being two such shafts, one on each side of the main conveyor 39, as shown in Figures 4 and 5. These shafts pass thru and are journaled in the frame members 10 and 10', and the brackets 26 on each side of the machine. Similarly, an intermediate shaft 43 extends longitudinally along each side of the machine thru all of the members 10, 10' and 26. A third shaft 44 extends thru these members below the shafts 43 at each side, as shown. These last two-mentioned shafts are idlers. Between each frame member 10 and 10' and between the two center members 10' on each side of the machine, these shafts 42, 43 and 44 carry sprocket wheels 45 adjacent these several frame members in such a manner that these sprocket wheels are arranged in sets lying in the same vertical planes, as can be seen in Figure 5. Chains 46 are trained around each set of sprocket wheels, and these chains have attached to their links, cross slats forming separate elevators or conveyors 47, there being in the embodiment illustrated, three such elevators on each side of the machine. All of these elevators are endless and, of course, follow the contour of the frame pieces 10, 10' in the camel back

formation shown. The brackets 26, heretofore mentioned, function as slat supports, as will be obvious.

Adjacent edges of the conveyers 47 are covered by shields 48, such shields also being provided along the free edge of the end conveyers. These shield strips 48 communicate with or abut against longitudinal shield strips 49 arranged at each side of the main conveyer 39, said shields being continued, as shown in Figures 1, 2 and 3, along the sides of the elevating part of the main conveyer at that end of the machine remote from the breaker. At this same end of the machine, the corners are rounded off and covered by shields 50, as shown. Guide members in the form of stationary or rotatable posts 51 are mounted on the strips 49 adjacent each conveyer or elevator 47, at a point with respect thereto, which is closest to the discharge end of the machine, for a purpose later to be made clear. The posts 51 for the endmost conveyer or elevator 47, that is, those adjacent the breaker, are provided with shields 52 which terminate in a tapered spout or funnel 53, said spout being in a position to feed between the rollers 32 embodied in the breaker.

In the operation of the improved feeder, the shaft 27, as seen in Figure 1, is driven from the breaker by means of the chain 29. In this manner the chains 34 are driven to operate the main, longitudinal, endless conveyer 39. Similarly, by means of the gears 40, the shafts 42 are oppositely rotated to operate the sprockets and chains for moving each of the endless elevators 47 toward the main conveyer.

Piles of slivers P, represented in Figure 2, are moved in place adjacent each elevator 47 and at the end of the main conveyer 39. These piles, having come from the first breaker, are such that the slivers are loose and not very well knitted together. An operator feeds the free end of the sliver from each pile P onto the adjacent elevator. The slats of these elevators are so constructed that they will best engage the slivers and elevate them onto the main conveyer, as indicated generally by the arrows in Figure 1. The posts 51 function properly to guide the slivers onto the main conveyer. The shields 48, 49 prevent the slivers from entangling and winding adjacent and between the several elevators, as will be understood, and between the elevators and the main conveyer. Of course, it can easily be seen that the camel back formation of the elevators is such that each will support its sliver as it elevates the same, and thus these slivers cannot become accidentally broken or disjointed because of their inherent looseness and weight. As the height of each pile decreases, the camel backs, due to their inclination toward each adjacent pile, will, of

course, have to feed a longer free length of sliver, but the inclination of each camel back will offer greater resistance to the longer sliver part and thus increase its effort toward preventing breakage, as will be obvious. In practice, it will be preferable to move the main conveyer at a somewhat slower speed than the side conveyers or elevators, as is indicated in the embodiment shown by the difference in size of the sprocket wheels 33 and the gears 40 on the drive shaft 27. The slivers move along the main conveyer 39 in the direction of the arrows and into the funnel or spout 53, which functions properly to direct these slivers between the rollers 32 of the second breaker.

It must be appreciated that the invention, one illustrative embodiment thereof having herein been disclosed, achieves all of the desirable objects heretofore recited, and that the same is relatively simple in construction and operation. It also very materially expedites the feeding operation, preventing sliver breakages in the process of handling. The machine also has a maximum capacity, as all sides thereof, except the discharge end, are put to use.

It is the intention herein to cover all such changes and modifications of the invention which do not depart from the spirit and scope thereof, as indicated in the subjoined claims.

What we claim as new is:

1. In a sliver feeder for breakers, the combination of a frame, a conveyer thereon leading to a breaker, an elevator for raising a sliver from a pile onto the conveyer, said elevator being inclined to support the sliver while elevating the same.

2. In a sliver feeder for breakers, the combination of a frame, an endless conveyer thereon including a substantially horizontal portion leading to a breaker, and an inclined elevator portion for raising a sliver from a pile onto the horizontal portion, said inclined portion acting to support the sliver while elevating the same.

3. In a sliver feeder for breakers, the combination of a frame, a conveyer thereon leading to a breaker, an elevator for raising a sliver from a pile onto the conveyer, said elevator being inclined to support the sliver while elevating the same, and means for driving said conveyer and elevator from the breaker.

4. In a sliver feeder for breakers, the combination of a frame, an endless conveyer thereon including a substantially horizontal portion leading to a breaker and an inclined elevator portion for raising a sliver from a pile onto the horizontal portion, said inclined portion acting to support the sliver while elevating the same, and a spout for directing the sliver from the horizontal portion into the breaker.

5. A feeder for breakers, said feeder comprising a longitudinally disposed main conveyer leading to a breaker, and a transversely disposed upwardly inclined elevator, for feeding a sliver onto the main conveyer. 70
6. A feeder for breakers, said feeder comprising a longitudinally disposed main conveyer leading to a breaker, and a plurality of transversely disposed, inclined elevators along one side of the main conveyer for feeding slivers thereto. 75
7. A feeder for breakers, said feeder comprising a longitudinally disposed main conveyer leading to a breaker, and a transversely disposed, inclined elevator on each side of the main conveyer for feeding slivers thereto. 80
- 15 8. A feeder for breakers, said feeder comprising a longitudinally disposed main conveyer leading to a breaker, and a plurality of transversely disposed, inclined elevators on each side of the main conveyer for feeding slivers thereto. 85
- 20 9. A feeder for breakers, said feeder comprising a main conveyer including an inclined elevator at one end thereof, and a series of right angularly disposed, inclined elevators for feeding slivers onto the main conveyer. 90
- 25 10. A feeder for breakers, said feeder comprising a main conveyer, and a plurality of opposed pairs of inclined elevators arranged at a right angle to said main conveyer and on opposite sides thereof for elevating and feeding slivers thereto. 95
- 30 11. A feeder for breakers, said feeder comprising a main longitudinally disposed conveyer leading to a breaker, and a transverse elevator formed with a camel back to support a sliver while feeding the same onto the main conveyer. 100
- 35 12. A feeder for breakers, said feeder comprising a main longitudinally disposed conveyer leading to a breaker, and a transverse elevator formed with a camel back to support a sliver while feeding the same onto the main conveyer, the top of said elevator terminating adjacent the side of the main conveyer and lying in substantially the same horizontal plane therewith. 105
- 40 13. A feeder for breakers as defined in claim 11 in which the main conveyer and elevator are endless. 110
- 45 14. A feeder for breakers, said feeder comprising a main longitudinally disposed conveyer embodying an inclined elevator at one end, transversely arranged camel backed elevators at the side of the main conveyer for supporting and elevating slivers onto the main conveyer, and shield members at the sides of the main conveyer and at the sides of the elevators. 115
- 50 15. A feeder for breakers, said feeder comprising a main longitudinally disposed conveyer embodying an inclined elevator at one 120
- 55 end, transversely arranged camel backed elevators at the side of the main conveyer for supporting and elevating slivers onto the main conveyer, shield members at the sides of the main conveyer, shield members at the sides and between the elevators, and guide members mounted on said first mentioned shield members for properly directing slivers from the elevators onto the main conveyer. 125
- 60 16. A feeder for breakers, said feeder comprising a main longitudinal conveyer leading to a breaker, an inclined elevator transversely disposed with respect to the main conveyer and communicating therewith, and a guide member cooperating with the elevator properly to direct material onto the main conveyer. 130
- 65 17. A feeder for breakers, said feeder comprising a main longitudinal conveyer leading to a breaker, an inclined elevator transversely disposed with respect to the main conveyer and communicating therewith, a shield member alongside the main conveyer, a shield member alongside the elevator, and a guide member on said first mentioned shield adjacent said last mentioned shield. 135
- 70 18. A feeder for breakers, said feeder comprising a main longitudinal conveyer leading to a breaker, a transverse, inclined elevator communicating with the main conveyor, guiding means for the material moving from the elevator to the conveyer, and a spout at the discharge end of the conveyer associated with said guiding means. 140
- 75 19. A feeder for breakers, said feeder comprising a longitudinal conveyer leading to a breaker, transverse, inclined elevators associated with the conveyer, a shaft having connections for driving the main conveyer, and connections from said shaft for driving the elevators. 145
- 80 20. A feeder for breakers, said feeder comprising a longitudinal conveyer leading to a breaker, transverse elevators associated with the conveyer, and means for driving said conveyer and elevators, said means driving the conveyer at a slower speed than the elevators. 150
- 85 21. The combination with a breaker, of a feeder therefor, said feeder comprising a frame carrying a longitudinal conveyer and a transverse, inclined, communicating elevator, a shaft on said frame connected to drive said conveyer and elevator, and means for driving said shaft from the breaker. 155
- 90 22. A feeder for breakers, said feeder comprising a frame, an endless longitudinal conveyer mounted thereon, an endless camel back transverse elevator carried by the frame to communicate with the conveyer, a shaft carried by the frame, and connections from the shaft for driving said conveyer and elevator. 160
- 95 23. A feeder for breakers, said feeder comprising a main conveyer leading to a breaker, 165

and means for simultaneously elevating slivers to said conveyer from a plurality of piles arranged alongside and at one end of said conveyer, said means embodying means for 5 constantly supporting the slivers during elevation thereof to prevent breakage of the slivers.

24. The method of feeding a sliver to a raised conveyer leading to a breaker, which 10 method comprises elevating the sliver from a pile on the floor adjacent the conveyer and constantly supporting the moving portion of the sliver substantially thruout its length during elevation from the pile to the conveyer to prevent its breakage.

25. The method of feeding slivers to a raised rectangular conveyer table leading to a breaker, which method comprises simultaneously elevating a plurality of slivers 20 from piles arranged at the sides of the conveyer table, and constantly supporting the

moving portions of said slivers substantially thruout their lengths during elevation from the piles to the conveyer table to prevent breakage of the slivers.

26. The method of feeding a sliver to a raised conveyer leading to a breaker, which method comprises elevating the sliver from a pile on the floor adjacent the conveyer and constantly supporting the free suspended 30 moving portion of the sliver thruout substantially its length during elevation from the pile to the conveyer and supporting it with an increased force as the pile lessens in height to impart to such lengthening moving part of the sliver an increased resistance tending to prevent its breakage.

In testimony whereof we affix our signatures.

GEORGE L. RICE.
LOUIE E. WHITCOMB.
